ABSTRACT

A device including an arm with proximal and distal ends, a telescope, a connector disposed in pivotal relation between the proximal end and the telescope and provided with a mechanism in engagement between the telescope and arm for intersection of the distal end and the axis of said telescope during rotation thereof.

METHOD OF LAYING A BALLISTIC MISSILE

CROSS-REFERENCE TO RELATED APPLICATION

This is a division of application Ser. No. 328,796, filed Feb. 1, 1973.

SUMMARY OF THE INVENTION

A ballistic missile including a level platform with an axis and a mirror in parallel relation thereto is disposed with the platform axis within $7\frac{1}{2}^{\circ}$ of a target azimuth by means of a compass (normal accuracy of the compass). The ballistic missile is limited to inflight corrections of 35 minutes of target azimuth misalignment.

The missile laying device is disposed with the proximal end in the axis of a north seeking apparatus and the connector and arm in aligned normal relation with the platform axis as determined by autoreflective relation of the telescope and the mirror.

The angular error between the platform axis position and the target azimuth is determined from the gyro apparatus and the telescope is rotated through an angle β proportionate to the angular error for normal relation of the telescope axis with the target azimuth. The platform axis is finally rotated into the target azimuth and normal relation with the telescope axis as determined by autoreflective engagement thereof with the mirror.

BRIEF DESCRIPTION OF THE DRAWINGS

FIG. 1 is a view of the laying device in engagement with a ballistic missile;

FIG. 2 is a cutaway view of the connector; and

FIG. 3 is a graphic illustration of the laying problem.

DESCRIPTION OF THE PREFERRED EMBODIMENT

A laying device 11 is provided with an arm 13 having a length L and a telescope 15 with a connector 17 having a length 1 in pivotal engagement therebetween. A ballistic missile 19 with shell 20 is provided with a level platform 21 having an axis 23 and a mirror 25 parallel to axis 23.

Connector 17 and arm 13 of the laying device are disposed for aligned normal relation with axis 23 as determined by autoreflective alignment of telescope 15 with mirror 25 and with proximal and distal ends 27 and 29 of arm 13 in respective engagement with the axis of a north seeking gyro device 31 and stable platform axis 23. In most cases a portion 32 of arm 13 is deleted to

provide virtual intersection of distal end 29 with axis 23 and prevent interference of arm 13 with shell 20 of the missile. Variable gear 33 is secured to telescope 15 and a spur gear 35 in rotatable engagement with arm 13 through pulleys 37 and belts 39 is biased by spring 41 into engagement with variable gear 33.

Variable gear 33 is disposed for coincidence of axis 43 of telescope 15 with distal end 29 during revolution of telescope 15.

In FIG. 3, $\alpha + \psi = 180^{\circ}$

$$\psi = 180^{\circ} - \alpha$$

$$\theta + \beta + \psi = 180^{\circ}$$

$$\theta + \beta = 180^{\circ} - \alpha = 180^{\circ}$$

$$\theta + \beta = \alpha$$

$$\tan \theta = d/L; d = L \tan \theta$$

$$d/\sin \beta = 1/\sin \phi \text{ where } \phi = (180 - [180 - (90 + \theta)])$$

$$= 90 + \theta$$

$$\sin \beta = d \sin (90 + \theta)/1 = L \tan \theta \sin (90 + \theta)/1 = L/1 \tan \theta \cos \theta$$

$$\sin \beta = L/1 \sin \theta$$

$$\beta = \sin^{-1}[L/1 \sin \theta]$$

OPERATION

Telescope 15 is rotated through angle β from the alignment position for normal relation of axis 43 of telescope 15 with target azimuth 45, and level platform 21 is rotated to autoreflective alignment of mirror 25 with telescope axis 43 to complete the laying of missile 11 to within $3\frac{1}{2}$ minutes of target azimuth 45.

We claim:

1. The method of laying in a target azimuth a compass-oriented ballistic missile having a stable platform with an axis and a mirror in parallel relation therewith, comprising:

determining from the north-seeking gyro device the angle θ between the platform axis and the target azimuth;

rotating the telescope through an angle β equal to $\sin^{-1}[L/1 \sin \theta]$ where L and 1 are the respective lengths of the arm and the connector; and

rotating the missile platform to autoreflective engagement of the telescope and mirror to lay the missile in the target azimuth.

UNITED STATES PATENT OFFICE
CERTIFICATE OF CORRECTION

Patent No. 3,851,844 Dated December 3, 1974

Inventor(s) William W. Stripling et al.

It is certified that error appears in the above-identified patent and that said Letters Patent are hereby corrected as shown below:

Column 2, line 13 should read $\gamma - \theta + \beta + 180 - \alpha = 180^\circ$ --.

Signed and sealed this 27th day of May 1975.
